UNITED STATES PATENT OFFICE.

FREDERICK E. SWOPE, JR., OF PHILADELPHIA, PENNSYLVANIA.

VARIABLE CONDENSER.

Application filed May 18, 1923. Serial No. 639,731.

My invention relates to an improvement in variable condensers, for example, such as are used in connection with radio receiving apparatus.

The object of my invention is to provide novel means for securing the fixed and movable plates of a variable condenser in order to insure correct alignment of the plates, reduce the parts, and enable the assembly 10 thereof with a saving of time and labor.

A further object of my invention is to provide a variable condenser, that is, one having fixed plates and relatively movable plates whereby the capacity may be varied, 15 which will be of novel construction and proof against warping with resultant short circuiting due to misalignment of the fixed and relatively movable plates.

Further objects of my invention are to produce a variable condenser which may be readily attached to the ordinary panel and which will be relatively inexpensive to construct and at the same time be durable and efficient in use.

Having now indicated in a general way the nature, purpose and advantage of my invention, I will proceed to a detailed description of a preferred embodiment thereof with reference to the accompanying drawings, in which—

Fig. 1 is a sectional view of a variable condenser embodying my invention.

Fig. 2 is a face view of a fragment of a panel showing the application of the condenser.

Fig. 3 is a sectional view on line 3—3 Fig. 1.

Fig. 4 is a sectional view on line 4—4 Fig. 1.

Fig. 5 is a view of a condenser plate.

Fig. 6 is a view of a plate supporting rod. *a, a'* represent heads or end plates of insulating material between which the fixed and relatively movable plates of the condenser are carried.

The fixed plates *c* are slotted as at *z* and are entered in slots or grooves *3* in rods *d, d'*. The rods are then squeezed longitudinally to close the slots *3* and secure the plates. The plates when secured on the rods *d, d'* are spaced equidistant by the lands *e* between the grooves *3* in the rods. The fixed plates are held against the head *a* by means of nuts *f*, and the rods *d, d'* carrying the plates *c*

are secured to the heads *a, a'* by means of nuts. A rod *g* carrying a spacer *h* is secured to the heads *a, a'*.

The relatively movable plates *i* of the condenser are carried on a rotatable shaft *j*, being slotted, as are plates *c*, for entry into slots or grooves similar to grooves *3* in rods *d, d'* in the shaft *j*. The plates are secured to the shaft by squeezing it longitudinally and when secured are spaced, by the lands *k*, to pass centrally between the fixed plates. Shaft *j* rotates on a bearing supported by heads *a'* and extends through an internally threaded hub *l* in head *a*. The movable plates are positioned between heads *a, a'* and in relation to fixed plates *c* by means of a spring *m* secured to head *a'*, embracing shaft *j* and bearing on a head *n* on shaft *j*. The spring *m* presses shaft *j* against its bearing on head *a'*, without exerting any pressure on head *a*, which would tend to separate the heads and throw the movable and fixed plates out of line. The spring also acts as a brake on the shaft *j* so that a fine adjustment may be made. The spring further may be used as an electrical contact, if desired.

The condenser is secured to the panel *o* by means of an externally threaded bushing *p* provided with an enlarged head *q*. The bushing passes through the panel and is threaded within the hub *l*, until the head *q* bears against the panel. An indicator hand *r* is threaded on the end of shaft *j*, as is a turning knob *s*.

Suitable leads *w* and *y* serve for connecting up the condenser.

Having now fully described my invention, what I claim and desire to protect by Letters Patent is:

1. A variable condenser comprising oppositely disposed heads, a solid rod provided with a circumferential slot extending between the heads and a condenser plate having a laterally opening slot engaged within the slot in said rod, the material forming the rod being expanded longitudinally adjacent opposite sides of the plate to secure the plate in the slot.

2. A variable condenser comprising oppositely disposed heads, a solid rod provided with spaced circumferential slots extending between the heads, a plurality of condenser plates having laterally opening slots engaged within the slots in the rod, the ma-

2
material forming the rods being expanded longitudinally between the plates whereby the slots in the rod are closed against the plates to secure the plates and rod together and afford electrical contact therebetween.

3. A variable condenser comprising oppositely disposed heads, a solid rod provided with alternate lands and grooves, condenser plates provided with laterally opening slots 10 engaged in said grooves, the lands on said rod being expanded to close said grooves against the plates and secure the plates therein.

4. A variable condenser comprising oppositely disposed heads of insulating material, a plurality of fixed plates mounted between said heads, a movable plate adapted to be moved between said fixed plates, and a spring secured to one of said heads and 20 acting on said movable plates in a direction away from the opposite head, whereby said movable plates are positioned between said heads.

5. A variable condenser comprising oppositely disposed heads of insulating material, a plurality of fixed plates mounted between said heads, a rotatable shaft, a plate mounted on said shaft, an end bearing for said shaft supported by one of said heads, and 30 a spring adapted to act to hold said shaft in said end bearing, said spring being secured to and acting in a direction toward the head supporting said bearing.

6. A variable condenser comprising oppositely disposed heads of insulating material, a plurality of fixed plates mounted between said heads, a bushing in one of said heads, a pin in the other head, a rotatable shaft 35 passing through said bushing and provided with an end bearing for said pin, a plate mounted on said shaft, and a spring secured to said last mentioned head and embracing said shaft, said spring acting in a direction

toward said last mentioned head to hold said shaft against said pin. 45

7. A variable condenser comprising oppositely disposed heads of insulating material, a plurality of fixed plates mounted between said heads, a bushing in one of said heads, a pin in the other head, a rotatable shaft 50 passing through said bushing and provided with an end bearing for said pin, a plate mounted on said shaft, a flange adjacent the end of said shaft, and a spring secured at one end to said last mentioned head, the 55 free end of said spring embracing said shaft and bearing against said flange, said spring acting in a direction toward said last mentioned head whereby said shaft is held against said pin and resistance to the rotation of the shaft is provided. 60

8. A variable condenser comprising oppositely disposed heads of insulating material, a plurality of fixed plates mounted between said heads, a bushing, having an internally 65 threaded portion, mounted in one of said heads, a panel, a bushing, having an internally threaded portion, adapted to thread into said first mentioned bushing, mounted in said panel, a rotatable shaft adapted to pass through said bushings and extend between said heads, a plate mounted on said shaft, a pin supported by the other head and adapted to support the end of the shaft, a 70 spring secured to said last mentioned head and adapted to act on said shaft in a direction toward said last mentioned head to hold the end of said shaft against said pin, and a knob on the end of said shaft adjacent said panel whereby said shaft may be rotated 75 manually. 80

In testimony of which invention, I have hereunto set my hand, at Philadelphia, Pa., on this 12th day of April, 1923.

FREDERICK E. SWOPE, JR.
